MACHINE SET

Franz Neugebauer, Dessau-Alten, Germany, assignor to Junkers Flugzeug-und-Motorenwerke Aktiengesellschaft, Dessau, Germany

Application June 8, 1937, Serial No. 147,064
In Germany June 15, 1936

8 Claims. (Cl. 60—13)

My invention relates to sets of machinery composed of a working machine such as a gas or liquid conveying machine and a power engine driving the working machine. It more particularly relates to means for driving the working machine with the aid of two power engines, from which power is transmitted to the working machine by means of a differential gear and one of which is a turbine which only intermittently transmits power on the working machine.

It has already been proposed to drive the scavenging or charging blower of an internal combustion engine by means of a waste gas turbine and a separate auxiliary driving engine, the driven revolving member of the blower being positively connected to the waste gas turbine and through a free wheel coupling to the auxiliary driving engine, for which, if desired, the crank shaft of the internal combustion engine may be substituted. Such a combination, however, involves the drawback that the total input of the blower must be supplied by the turbine whenever it is running at a higher angular velocity than the other driving engine.

It has also been suggested to drive a working machine (viz. the scavenging and charging blower of an internal combustion engine) by means of two power engines, one of which is a waste gas turbine, while the other may be an electromotor, these engines driving the blower through a differential gear in such manner that the outputs of both engines are transmitted to the blower irrespective of their speeds. In connection with such an arrangement it has been suggested to block the waste gas turbine or the member of the differential gear connected to it by means of a brake whenever no driving fluid is supplied to the turbine, particularly when starting the internal combustion engine, in order to prevent a reverse run of the turbine owing to a lack of waste gas pressure sufficient for the production of a torque, an undesired reduction of the driving speed of the scavenging and charging blower being thus avoided. Here, however, the drawback is involved that a brake is required to block the turbine and that after unlocking the brake the turbine must be speeded up from stoppage so that the turbine operates within a disadvantageous range of its efficiency characteristic.

It is an object of my invention to provide means for driving a working machine by means of two power engines transmitting power to the working machine through a differential gear, one of the engines being an intermittently driving

turbine, the drawbacks mentioned above being however avoided.

I obtain this according to this invention by inserting a free wheel coupling between two members of the differential gear that would rotate relative to each other, if the working machine is assumed to be stopped and no driving fluid is delivered to the turbine, while the other power engine is running. Thus the free wheel coupling will couple the members whenever no driving fluid is delivered to the turbine, so that the working machine is driven and the turbine rotated in its normal direction of rotation, the free wheel coupling being disengaged only when owing to the delivery of driving fluid the turbine runs at higher speed. In such an arrangement locking brakes can be dispensed with since the turbine is driven in its normal direction even if no driving fluid is delivered to it, and therefore already runs at an initial speed when the fluid is delivered to it so that it can operate within a more advantageous range of its efficiency characteristic as compared to an acceleration from rest.

In the drawings affixed to this specification and forming part thereof some embodiments of my invention are illustrated diagrammatically by way of example.

In the drawings—

Figs. 1 and 3 to 7 are diagrammatic illustrations of some embodiments, each figure showing a working machine, two power engines, and a differential gear, the latter partly in section.

Fig. 2 is an enlarged section on the lines II—II of Fig. 1.

Figs. 8 to 9 illustrate the combination of an arrangement according to this invention with the scavenging and charging pump of an internal combustion engine.

In all figures corresponding parts are designated by the same reference numerals.

Referring first to Figs. 1 and 3 to 5, A is a power engine, the shaft 1 of which carries a toothed bevel wheel 3 forming part of an epicyclic gear. B is a turbine, the shaft 2 of which carries another toothed bevel wheel 4, also forming part of the epicyclic gear constituting the differential gear. The latter further comprises a bevelled planet wheel 5 engaging both wheels 3 and 4 and supported by a cage 6 rotatably mounted on the shafts 1 and 2. On the cage 6 is formed a toothed rim 7 engaging a toothed wheel 8 mounted on the shaft 9 of the working machine C.

Referring more particularly to Figs. 1 and 2, a free wheel coupling is inserted between the

wheel 3 and the cage 6 of the differential gear. The coupling comprises jamming members such as rollers or balls 11 arranged between an outer member 12 rigidly connected to or integral with the cage 6, and an inner toothed or cam member 10 keyed on to the shaft 1, the outer surface of the member 10 being formed in the manner shown in Fig. 2, with gradually sloping recesses.

The operation of this device is as follows: Whenever the power engine A drives the shaft 1 in the direction indicated by the arrow *a* in Fig. 2 and no driving fluid is delivered to the turbine B, the free wheel coupling will couple the shaft 1 and the cage 6, wheel 3 and cage 6 rotating at equal speeds so that the wheel 4 and the running member of the turbine B will be driven at equal speed. If, however, the turbine being supplied with driving fluid, produces a driving torque, the shaft 1 will lag behind the cage 6 so that the free wheel coupling will be released and power will be transmitted from both engines A and B to the working machine C through the differential gear.

In the modified form shown in Fig. 3 the free wheel coupling is inserted between the wheels 3 and 4 of the differential gear. It comprises an outer member 15 rigidly secured to the wheel 4 and surrounding the jamming members 14, while the inner member 13 is secured against rotation on an extension 1' of the shaft 1.

In the embodiment of Fig. 4 the free wheel coupling is inserted between the planet wheel 5 and its supporting pin 16 and comprises an outer portion 19 connected to wheel 5, an inner portion 17 connected to the pin 16, and jamming members 18.

According to Fig. 5 a similar free wheel coupling comprising an inner member 20, jamming members 21 and an outer member 22, is inserted between the shaft 2 and the cage 6, the outer member 22 of the coupling being formed integral with the cage and the inner member 20 being fixed on the shaft 2.

The operation of the devices shown in Figs. 3 to 5 is substantially the same as that of the device shown in Figs. 1 and 2 and need not be explained in detail.

Figs. 6 and 7 illustrate further embodiments of this invention in which spur gear wheels are used instead of bevel gears.

Referring to Fig. 6, the shaft 1 of the power engine A carries a wheel 25 formed with an inner toothed rim, while the shaft 9 of the working machine C carries a toothed sun wheel 26. The cage 28 of the differential gear, which carries the planet wheel or wheels 27, is formed with an outer toothed rim 29 engaging a gear wheel 30 which is mounted on the shaft 2 of the turbine B. Between the shaft 1 and the cage 28 a free wheel coupling comprising the members 31, 32, 33 is inserted, which couples the shaft 1 with the cage 28, whenever the power engine A is running and no driving fluid is delivered to the turbine B, the working machine C running at the same speed as the power engine A and the turbine running at a speed determined by the ratio of the toothed wheels 29 and 30.

The embodiment shown in Fig. 7 differs from that shown in Fig. 6 in that the power engine A and the turbine B are exchanged, the toothed rim 125 being mounted on the shaft 2 of the turbine B, the shaft 1 of the power engine A carrying a toothed wheel 39 engaging a toothed rim 38 being mounted on the external member 37 of the free wheel coupling 35, 36, 37, member 37 being

integral with the cage 128 of the differential gear.

Fig. 8 illustrates my invention as applied to the driving of the scavenging and charging blower C₁ of an internal combustion engine. The discharge side of the blower C₁ is connected by means of a pipe 46 to the intake ports (not shown) of the cylinders 45 of the internal combustion engine M. The blower is driven by a power engine A₁ (electromotor) and a waste gas turbine B₁, to which the exhaust gases of the engine M are fed through a pipe 47 connecting the exhaust ports (not shown) of the cylinders 45 to the turbine B₁. Power is transmitted from the power engine A₁ and the waste gas turbine B₁ to the blower C₁ through the differential gear, the wheel 50 of which is mounted on the shaft 51 of the power engine A₁, while the wheel 52 is mounted on the shaft 53 of the waste gas turbine B₁. The cage 55 carrying the planet wheels 54 is formed with an outer toothed rim 56 engaging a wheel 57 mounted on the shaft 58 of the blower C₁. A free wheel coupling 60, 61, 62 is inserted between the shaft 51 of the power engine A₁ and the cage 55 of the differential gear. The inner member 60 of the coupling is fixed on the shaft 51, the outer member 62 enclosing the jamming members 61 is secured to the cage 55. The operation of the differential gear is similar in all respects to that of the gear described in connection with Fig. 1.

Fig. 9 illustrates similar means for driving the scavenging and charging blower C₁ of an internal combustion engine, the only difference being that the internal combustion engine M is here relied upon to drive the blower C₁. In order to accomplish this, the wheel 150 of the differential gear is mounted on a shaft 65 supported in bearings 63 and 64 and connected to the crank shaft of the internal combustion engine M by means of a clutch 66. Thus an additional power engine, such as A₁ in Fig. 8, is dispensed with in the combination shown in Fig. 9.

I wish it to be understood that I do not desire to be limited to the exact details of construction shown and described for obvious modifications will occur to a person skilled in the art.

Various changes may be made in the details disclosed in the foregoing specification without departing from the invention or sacrificing the advantages thereof.

I claim:

1. A machine set comprising in combination a working machine, a turbine, another power engine, a differential gear for transmitting power from said turbine and said engine to said machine and an overrunning clutch inserted between two relatively rotating members of said gear and coupling said parts, until the speed of said turbine exceeds that of said engine.

2. The machine set of claim 1, in which the differential gear comprises two main wheels, a planet wheel and a cage carrying said planet wheel.

3. The machine set of claim 1, in which the differential gear comprises two main wheels, a planet wheel and a cage carrying said planet wheel and the overrunning clutch is inserted between two parts of said differential gear.

4. The machine set of claim 1, in which the differential gear comprises two main wheels, a planet wheel and a cage carrying said planet wheel and the overrunning clutch is arranged between one of said main wheels and said cage.

5. The machine set of claim 1, in which the differential gear comprises two main wheels, a planet wheel and a cage carrying said planet wheel.

- wheel and the overrunning clutch is arranged between said two main wheels.
6. The machine set of claim 1, in which the differential gear comprises two main wheels, a planet wheel and a cage carrying said planet wheel and the overrunning clutch is arranged between said planet wheel and said cage.
7. The machine set of claim 1, in which the working machine is the scavenging and charging blower of an internal combustion engine and the
- turbine is a waste gas turbine driven by the exhaust gases of said engine.
8. The machine set of claim 1, in which the working machine is the scavenging and charging blower of an internal combustion engine which forms the other power engine, while the turbine is a waste gas turbine driven by the exhaust gases of said engine. 5
